(57) **CLAIM**

The ornamental design for a mixing well with cover, as shown and described.

DESCRIPTION

FIG. 1 is a top perspective view of the mixing well with cover, showing our new design;

FIG. 2 is a bottom perspective view of the mixing well with cover of FIG. 1;

FIG. 3 is a top plan view of the mixing well with cover of FIG. 1;

FIG. 4 is a bottom plan view of the mixing well with cover of FIG. 1;

FIG. 5 is a front elevational view of the mixing well with cover of FIG. 1;

FIG. 6 is a left side elevational view of the mixing well with cover of FIG. 1;

FIG. 7 is a rear elevational view of the mixing well with cover of FIG. 1;

FIG. 8 is a right side elevational view of the mixing well with cover of FIG. 1;

FIG. 9 is a top perspective view of the mixing well shown in isolation, without the cover;

FIG. 10 is a bottom perspective view of the mixing well shown in FIG. 9;

FIG. 11 is a top plan view of the mixing well shown in FIG. 9;

FIG. 12 is a bottom plan view of the mixing well shown in FIG. 9;

FIG. 13 is a front elevational view of the mixing well shown in FIG. 9;

FIG. 14 is a left side elevational view of the mixing well shown in FIG. 9;

FIG. 15 is a rear elevational view of the mixing well shown in FIG. 9;

FIG. 16 is a right side elevational view of the mixing well shown in FIG. 9;

FIG. 17 is a top perspective view of the cover in isolation, without the mixing well;

FIG. 18 is a bottom perspective view of the cover shown in FIG. 17;

(Continued)

FIG. 19 is a top plan view of the cover shown in FIG. 17;
 FIG. 20 is a bottom plan view of the cover shown in FIG. 17;
 FIG. 21 is a front elevational view of the cover shown in FIG. 17;
 FIG. 22 is a left side elevational view of the cover shown in FIG. 17;
 FIG. 23 is a rear elevational view of the cover shown in FIG. 17; and,
 FIG. 24 is a right side elevational view of the cover shown in FIG. 17.

The claim is directed to the collective appearance of all elements shown.

The broken lines in the drawing views are included for the purpose of illustrating portions of the mixing well that form no part of the claimed design.

1 Claim, 12 Drawing Sheets
